UNITED STATES PATENT OFFICE.

EMIL L. CLAUS, OF MILWAUKEE, WISCONSIN, ASSIGNOR TO MILWAUKEE GAS SPECIALTY COMPANY, OF MILWAUKEE, WISCONSIN, A CORPORATION OF WISCONSIN.

IGNITION DEVICE FOR GAS BURNERS.

Application filed August 19, 1920. Serial No. 404,588.

To all whom it may concern:

Be it known that I, EMIL L. CLAUS, a citizen of the United States, and resident of Milwaukee, in the county of Milwaukee and 5 State of Wisconsin, have invented certain new and useful Improvements in Ignition Devices for Gas Burners; and I do hereby declare that the following is a full, clear, and exact description thereof.

10 My invention relates to new and useful improvements in devices adapted for association with a gas stove or the like to light any one of a plurality of burners thereof, the present structure constituting a general 15 improvement of the ignition apparatus disclosed in my previous Patent No. 1,339,102, issued to me May 4, 1920, and wherein there is provided a plurality of valves associated with respective burners and a torch-head 20 having ports individually connected each with an igniter port of a respective valve whereby when the valve is opened, an igniting torch of flame is projected toward the corresponding burner.

25 It is in general an object of the present invention to simplify the structure of the present type of device and to reduce the number of exposed parts whereby to facilitate maintaining the device in cleanly condition and to effect a most pleasing appearance of the device when associated with a gas stove. In providing for the projection of individual jets, it is necessary to provide a passageway extending from each 30 of the main valves to the torch-head and it is more particularly an object of my present invention to embody such passageways in the main supply pipe or stringer structure of the stove.

35 It is a further important object of my invention to provide an arrangement facilitating the manufacture and assembly of the main and torch supply valves with respect to the various gas passageways with which 40 they are associated.

A still further object resides in the provision of an improved torch-head structure which may be most readily associated with the supply passages for individual jets thereof; which is provided with jets adapted to effect a most positive discharge of the igniting gas and to permit adjustment for varying the range of action of the jet of igniting gas, and which further is adapted

to maintain pilot ignition of gas therein in 55 such manner as to effectively guard against possible extinguishing of the same.

A still further object with respect to the pilot ignition of the torch-head resides in the provision of means for selectively maintaining a pilot light at one or a plurality of the jets, and for adjusting the size of the pilot light or lights whereby to adapt the device for use with different grades and pressures of gas, and different conditions of 60 exposure to drafts, tending to extinguish the pilot ignition.

With the above and other objects and advantages in view, my invention resides more particularly in the novel combination, formation and arrangement of parts herein-after described and pointed out in the appended claims.

In the accompanying drawings—

Figure 1 is a plan view of a gas stove 75 having my improved lighting device associated therewith;

Figure 2 is a sectional view taken longitudinally through the torch supply pipe of the device and showing its connection with 80 the stringer and passages thereof;

Figure 3 is a plan view of the torch-head pipe, with portions of the stringer pipe and torch-head in section;

Figure 4 is a vertical sectional view taken 85 longitudinally through the stringer pipe on the plane indicated by line 4—4 of Figure 2;

Figure 5 is a vertical sectional view through one side portion of the torch-head base;

Figure 6 is a sectional view through one of the control valves and the adjacent stringer pipe portion;

Figure 7 is a horizontal view through the valve showing the various working positions 95 thereof, and

Figures 8 and 9 are horizontal and vertical views taken respectively through a modified form of passageway structure connecting the stringer pipe and torch-head.

Referring now more particularly to the accompanying drawings, 10 designates the top of a conventional gas stove, including in the present instance four burners 11 from which the usual pipes 12 extend to the front of the stove and terminate in air-mixing heads 13 receiving the discharge nipples of conventional control valve casings 14, the

intake nipples of said valves being threaded in the usual main supply pipe or stringer 15 which extends along the front of the stove.

In the present instance I utilize the 5 stringer pipe 15 to house the individual torch jet passages, and thus a pair of relatively small pipes 16 are secured in the stringer pipe at its side portion receiving the valves. These torch-supply pipes may be 10 secured to the stringer pipe in any suitable manner, and in the present instance they are laid in the stringer pipe and brazed thereto, being suitably held for the brazing operation, whereby to facilitate ready and 15 economical manufacture. The stringer pipe is bored and tapped to provide the usual threaded valve-receiving openings and opposed portions of the torch pipes 16 are simultaneously apertured inasmuch as the 20 axes of the valve-receiving openings extend between the torch-pipes 16, and when the intake nipple of each gas control valve is threaded in the corresponding opening, the torch-pipe openings are closed with respect 25 to the interior of the stringer pipe and opposite sides of the intake nipple are exposed in the pipes 16.

It will be noted that the dimensions of the torch-supply valve are of the usual U. 30 G. I. standard in the present instance with the exception that the intake nipple is slightly longer than standard so as to extend past the apertures of the torch pipes 16 and properly close the same. The outlet port 17 of the valve casing is located in its usual position, but the intake port 18 is slightly offset from the center of the intake nipple of the casing to supply clearance for a relatively small torch-supply port 19, 35 which is drilled longitudinally in the nipple, said port 19 extending from the well of the casing and having its outer end closed by a plug 20. A transverse bore 21 connects the port 19 with the interior of either of the pipes 16 when the valve is threaded in place. The usual valve plug 22 is secured in the well of the casing 14 and carries a handle 23 above the stringer pipe and this plug is provided with the usual transverse 40 port 24 for connecting the intake and discharge ports 18 and 17 respectively, the end portions of the port 24 being offset in accordance with the offsetting of the casing ports, and being hence formed by drilling in from 45 opposite sides of the plug. The port 24 is slightly horizontally widened so as to freely admit gas through the main ports when the handle 23 is swung slightly past its "full on" position extending transversely at right angles across the stringer, it being noted 50 that the handle in the present valve is permitted a degree of rotation slightly greater than a quarter turn to permit this movement past "full on," which constitutes the "flash" 55 position for the valve. The plug is further 60 provided with a bore 25 extending obliquely 65 therein from a peripheral point which is in the plane of the torch port 19, this bore 25 meeting the main port 24 at the shoulder formed by its offset formation, and the port 70 25 is in communication with the torch port 19 when the valve handle is in flashing position.

Thus, gas is supplied through the valve to its corresponding burner in entirely conventional manner and when the valve handle is swung past its "full on" position the portion of the gas entering the intake nipple for the main supply flow will pass backwardly through the intake nipple and into one of 75 the torch supply pipes 16, and when the valve handle is turned back to its "full on" position this torch supply will be cut off and the valve will function in its usual manner, it being particularly noted that, by the 80 economy of bores to effect the various port connections described, I am enabled to retain substantially the usual standard construction and size of the valve.

In the present structure there are a pair 85 of valves at each side of the center of the stringer pipe, and the torch-supply ports 19 of these valves are disposed respectively at the top and bottom portions of the intake nipples with a corresponding location of 90 the bores 21 whereby one valve in its flash position is adapted to discharge a torch flow of gas into the upper pipe 16 while the other valve is adapted to discharge a torch flow of 95 gas into the lower pipe 16.

To connect these flows of gas with corresponding jets of a torch-head, a torch-head carrying member is provided having a series of longitudinal passages to effect its connections, and in the present arrangement this member is in the form of a pipe 26 having inserted therein a bar 27 provided with four concave sides defining in conjunction with the inner periphery of the pipe a corresponding number of passageways. This pipe is closed at its inner end and is threaded into a bore formed in the central portion of the stringer pipe. The cutting of this bore also cuts the pipes 16 in a single boring operation and the end of the pipe 26 closes the hence formed apertures in the pipes 16. Ports 28 are formed in the wall of the pipe 26 which connect the pipe 16 with the longitudinal passageways defined in the pipe 26 by the bar 27 and thus an exceedingly simple and readily manufactured and assembled connection is provided. The pipe 26 extends inwardly of the stove to substantially a central point and carries the torch-head of the 100 device.

This torch-head comprises an elbow base member in the form of an angular casting 29 having one arm provided with a threaded socket 30 and having its other arm 105 upwardly and provided with a central pas-

sageway which extends entirely through the member, said upstanding portion being provided with a series of vertical bores 31 grouped about its central opening, and the sides of the upstanding portion are cut away between these bores to provide air inlets for the lower portion of a hood cylinder 32 secured on the base member preferably by a set screw 33 engageable in a peripheral groove of the upstanding portion. Air is also admitted to the hood cylinder through the central aperture of the base member. The horizontal leg of the torch head base member is provided with a series of bores 34 extending inwardly from its end and grouped about the pipe-receiving socket 30, each of these bores intersecting a corresponding vertical bore 31, the lowermost bores 34 being hence extended through the base member at the sides of its central opening for communication with the more remote bores 31. The outer ends of the bores 34 are closed by suitable plugs 35 and oblique bores 36 extend inwardly from the socket 30 for communication therewith, these bores 36 registering with radial bores 37 formed in the end portion of the pipe within the socket and thus affording communication between the longitudinal passages of the pipe 26 and the various series of connecting bores whereby independent torch flows of gas may be delivered at the top of the base member through the vertical bores 31. A series of angular torch tips 38 are provided, each having one leg threaded in the upper portion of a corresponding bore 31 and having its other leg directed inwardly and arranged to discharge its jet inwardly of the group of jets and between an opposite pair of jets toward a respective burner, as set forth in my aforementioned patent. The jet passage of the horizontal leg of each angular torch tip is bored from its angle portion, the resultant opening at the angle being closed by a plug 39 and the jet passage is relatively long and slightly tapered toward its point of discharge whereby to provide a positive and accurate jet which will carry flame a maximum distance with a given general gas pressure. By threading the torch tips in the base member, a means is provided for adjusting the direction of said tips within a fairly wide range, so that a standard torch head structure may be adapted for conditions of use incidental to various types of stove tops, and the torch flow of each tip may obviously be directed to either side of the diametrically opposed tip in accordance with the location of the particular burner which it is desired to ignite by a torch projection from the tip. The hood cylinder 32 is provided with a series of circumferentially elongated firing ports 40, and to adjust the position and area of these ports to meet variable conditions of draft or burner location, a ring 41 is rotatably mounted on the hood cylinder and is provided with a corresponding series of horizontally elongated firing ports 42 whereby adjustment 70 of the ring will procure variation of the extent and location of the effective port area. A screen 43 extends across the lower inlet area of the torch hood, being disposed in the present instance on the base member 29, 75 and a second screen 43' is disposed in an outwardly bulged upper portion of the hood cylinder, the cylinder above said screen being closed by a cap plate 44 and being provided with a series of inlet openings 45 80 which are shielded by said cap plate, the plate being held in place by the heads of screws 46 threaded therein and engaging the inturned upper edge of the hood.

It is noted that, to light a burner at one side of the stove it is necessary to project a flame from the remote side of the torch head and hence to provide for control of both the torch and burner flow of gas by the corresponding burner valve, it is necessary for the passageways embodied in the pipe 26 to mutually cross in their extension to the torch head. In the present arrangement, I effect this mutual crossing of the passages by imparting a twist of 180° to the intermediate portion of the bar 27 prior to its assembly in the pipe 26, and thus the torch flows of gas from the valves at one side of the gas burner are transmitted to the torch tips at the opposite side of the torch head and inasmuch as each burner supply valve may deliver selectively to either the upper or lower torch passageway of the stringer pipe, in accordance with the location of its discharge bore 21, a ready assembly for the proper co-relation of ports, valves and burners may be effected. It will be further noted that a considerable range is afforded for the registering of the communicating apertures for the various passageways, whereby to facilitate the manufacture of the device under conditions of quantity production.

Slight flow of gas to maintain a pilot light at either one or a plurality of the torch tips may be effected by aperturing one or a plurality of the series of passageways within the stringer pipe. In the present instance, I provide for a regulated control and adjustment of the pilot light to meet the various conditions of gas quality, pressure and torch head draft which would be encountered in general use of the invention. Hence, in the present arrangement the closed end of the pipe 26 within the stringer pipe is provided with a series of valve-seating apertures 47 which communicate with the respective passageways formed within the pipe by the bar 27. A plug 48 is threaded 110 in the opposite portion of the stringer pipe, 115

120

125

130

and a series of needle valves 49 are threaded in this plug and may be thus independently adjusted to open or close the pilot supply apertures of the various passageways so that 5 a pilot light of any desired size may be maintained with respect to either one or a plurality of the torch tips, it being noted that under favorable conditions, a single pilot light of small size will be effective in 10 my device by reason of the close grouping of the tips and by the direction of the torch flow of gas inwardly through the group of tips, this feature being covered broadly in my aforementioned patent.

15 I have thus provided an exceedingly simple and readily manufactured and assembled device whereby upon opening any one of the plurality of main supply valves, a flow of gas will be provided for the corresponding burner and a torch flow of gas will be similarly provided for the corresponding individual torch tip whereby simultaneously with the action of supplying the gas a single jet will be projected at the proper time for 20 igniting the gas, providing a unitary operation requiring only a single movement by one hand of the operator, thus producing an economy of effort and an economy of gas by the provision of the single torch jet in 25 contradistinction to the heretofore provided multiple torch jets operated by independent valve means although it will be appreciated that various features of my invention are independent of the projection of an individual torch flow inasmuch as an exceedingly important feature of my invention resides 30 in the general connection of the torch head and the various valves by means forming a rigid part of the stringer pipe.

35 In Figures 8 and 9, I show a modified structure embodying individual tube connections between the bores of the torch head and the torch passageways of the stringer pipe. In this structure the torch passageways of the stringer pipe constitute a pair of relatively small pipes 51 at each side of the center of the stringer, said pipes having their adjacent ends opposed and mutually closed in the present instance by plugs 40 52 threaded in their adjacent ends, the valve supply of torch flows of gas to the passageways formed by these pipes being identically the same as in the afore-described structure.

45 The stringer pipe is provided with a group of bores in its inner side which extend through the respective passageway pipes 51 immediately adjacent their mutual closure plugs 52 and a series of short tube sections 53 are threaded in these bores and communicate with the pipes 51. Coupling sleeves 54 are telescoped on the tube sections and torch head tubes 55 are threaded in the outer ends of these coupling sleeves. Thus, torch flow of gas may be conducted from the 50 stringer pipe passageways to the torch head

tubes 55. A casing 56 is disposed about these couplings, having ears 57 at one end secured to the stringer pipe by screws 58 and a reducing pipe section 59 is threaded in the other end of the casing and is connected with a casing pipe 60 which is disposed about the converged and closely grouped intermediate stretch of the tubes 55. A transverse plate 61 is disposed in the casing 56 and apertured to receive the tubes 55, with one side of the plate in abutment with the shoulders formed by the ends of the coupling sleeves 54, while the upper side of the plate is abuttingly engaged by the end of the reducing pipe section 59 when 60 threaded into the casing, to provide a proper tightness of the joints formed by the coupling sleeves 54 which are telescopingly slidable on the tube sections 53. A pipe section 62 is slidable on the pipe 60 and has one end projected beyond the pipe 60 and flattened to provide for angular divergence of the torch head tubes 55 in their connection with the torch head. The torch head in the present modified structure comprises 65 a base ring 63 having a series of passageways 64 extending therethrough and elbow couplings 65 are threaded connected with the lower portions of said passageways. Each of these elbow couplings comprises a 70 relatively long arm and a relatively short arm, and inasmuch as the torch head tubes are disposed in superposed pairs, the uppermost tubes are connected with the relatively long arms of the couplings, while the lower tubes are connected with the relatively short arms of the couplings, thus providing for 75 the use of a single type of coupling. A hood member 66 is carried by the base ring 80 85 90 95 100 105 110 115 120 125 130 135 140 145 150 155 160 165 170 175 180 185 190 195 200 205 210 215 220 225 230 235 240 245 250 255 260 265 270 275 main supply pipe therefor, of a pair of torch supply pipes extending along the main supply pipe, a plurality of valves having their intake nipples secured in the main supply pipe between the torch-supply pipes and engaging said torch-supply pipes, connections between said valves and the burners, main supply ports in said valves communicating with the main supply pipe, 10 torch-supply ports in said valves each communicating with one of the torch-supply pipes, a torch-head provided with a plurality of jets, and connections between the torch-supply pipes and corresponding jets 15 of the torch-head.

3. An igniter device comprising the combination with a plurality of burners and a main supply pipe therefor, of a pair of torch-supply passageways extending along the main supply pipe, burner supply valves secured in the main supply pipe and connected with the burners, a torch-supply port in each valve connected with one passageway, a member secured in the main supply pipe and interrupting said torch-supply passageways, said member being provided with longitudinal passageways communicating with the torch supply passageways, and a torch-head carried by said member and provided with jets communicating with the passageways of said member.

4. An igniter device comprising the combination with a plurality of burners and a main supply pipe therefor, of a plurality of passageways extending along the main supply pipe, burner supply valves communicating with the main supply pipe each having a torch-supply port communicating with one of said passageways, a member threaded in the main supply pipe and having longitudinal passageways communicating one with each of the first named passageways, and a torch-head carried by said member and provided with jets communicating one with each of the said passageways of the member.

5. An igniter device comprising the combination with a plurality of burners and a main supply pipe therefor, of a plurality of passageways extending along the main supply pipe, valves communicating with the main supply pipe each having a torch-supply port communicating with one of said passageways, a pipe threaded in the main supply pipe and closed with respect to communication therewith, a member secured in said pipe and defining a plurality of passageways therein, each of said last named passageways communicating with one of the torch-supply passageways, and a torch-head carried by said member and having torch jets communicating with the said passageways thereof.

6. An igniter device comprising the combination with a plurality of burners and a main supply pipe therefor, of a plurality of

passageways extending along the main supply pipe, a torch-head member threaded in the main supply pipe and having longitudinal passageways closed with respect to the main supply pipe and communicating with the first specified passageways, a plurality of valves at each side of said torch head member and connected with respective burners, 2 main supply ports in each valve, a torch port in each valve connected with one of the first named passageways, a torch-head carried by said torch-head member and having torch jets directed toward respective burners, and the passageways of said torch-head member being arranged spirally there- 80 in whereby a valve at one side of the torch-head member is adapted to supply gas to a corresponding jet at the opposite side of the torch-head.

7. An igniter device comprising the combination with a plurality of burners and a main supply pipe therefor, of a plurality of passageways extending along the main supply pipe, a pipe threaded in the main supply pipe and closed with respect to communication therewith, a bar secured in said pipe to define a plurality of passageways therein, said bar being twisted to impart a spiral direction to portions of said passageways, each of said last named passageways communicating with one of the torch supply passageways, valves each having their inlet nipple secured in the main supply pipe at the sides of the last specified pipe, a main supply port in each valve, a torch supply port in each valve communicating with a torch passageway, and a torch head carried by said last specified pipe and having torch jets communicating with the passageways thereof.

8. In an igniter device, a valve casing provided with intake and discharge nipples and with a well, intake and discharge ports extending through the respective nipples, one of said ports being eccentrically located in the nipple, a torch-port extending longitudinally in the specified nipple, a valve plug disposed in the well and provided with a transverse port having its terminal portions relatively eccentric, and a torch port in the plug communicating with the first named port and adapted to communicate with the torch supply port of the casing.

9. An igniter device comprising the combination with a burner and a main supply pipe therefor, of a torch supply passageway extending along the main supply pipe, a valve-casing having an intake nipple secured in the main supply pipe and provided with a well, intake and discharge ports in the valve casing, a torch-port extending longitudinally through the intake nipple and communicating with the well, the end of said port being closed in the main supply pipe, said nipple being provided

with a transverse bore connecting the torch supply port with the torch supply passageway, a plug in the well of the casing provided with a transverse bore connecting the 5 intake and discharge ports of the casing and provided with a torch port communicating with said transverse port and adapted to communicate with the torch port of the casing, and a torch-head connected with said 10 torch supply passageway.

10. An igniter device comprising the combination with a plurality of burners and a main supply pipe therefor, of a pair of torch-supply pipes secured in the main 15 supply pipe, burner valves communicating with the main supply pipe each having a torch supply port connected with a torch supply pipe, the intermediate portion of the main supply pipe being provided with 20 a bore extended through the contiguous portions of the torch supply pipes, a torch-head pipe having one end secured in said bore and closing said torch-supply pipes with respect to mutual communication, said 25 torch-head pipe being provided with longitudinal passageways and being apertured within the main supply pipe to provide communication between said passageways and the torch supply pipes, and a torch-head 30 carried by said torch-head pipes and having torch jets communicating with the said passageways thereof.

11. In an igniter device, the combination of a torch head base member provided with 35 a series of jet supply passageways, and a plurality of angular tip members each having one end portion threadedly connected with the base member in communication with the passageways thereof, the other end 40 portions of the tip members being directed inwardly of the group of said members for discharge between a pair of opposed members, said other end portions of the tip members being bored from the angles of the tip 45 member to provide discharge passageways taperingly reduced.

12. An igniter device including a member provided with longitudinal passageways therein, means for supplying gas selectively 50 to said passageways, a torch-head base member provided with a socket receiving said passageway member, said torch-head base member being provided with angular bores having receiving portions grouped about 55 said socket and having their discharge portions terminating at the upper portion of the base member, jet tips communicating with the discharge portions of said bores, and said passageway member being provided with radial openings for connecting 60 the passageways of said members with the receiving portions of the torch-head bores.

13. In an igniter device, the combination of a torch-head base member provided with 65 a central aperture, a hood secured on said

member, angular bores in said member open at the upper portion of said member, means for supplying individual flows of gas to said angular bores, and torch tips disposed within said hood and communicating with said bores, each tip being arranged to direct its torch jet between an opposite pair of tips. 70

14. In an igniter device, the combination of a torch-head member, a plurality of torch tips carried thereby and adjustable to vary 75 the direction of torch jets discharged thereby, a hood disposed about said tips and provided with firing ports, and a band carried by the hood and provided with corresponding port apertures, said band being rotatable 80 with respect to the hood to adjust the location and effective area of the firing ports.

15. In an igniter device, the combination of a torch-head member, torch tips carried by said member, a hood disposed about said 85 tips and provided with firing ports and with apertures above said firing ports, lower portions of the hood space being open to permit inlet of air, and screen members in the hood above and below the firing portions of said tips. 90

16. An igniter device comprising the combination with a plurality of burners and a group of torch jets, of individual torch supply passageways communicating with 95 said jets, means for supplying torch flow of gas selectively to said passageways, a main supply pipe, portions of said torch supply passageways being grouped at one side of the main supply pipe, a plug threaded in said pipe opposite said grouped portions of the passageways, said grouped portions of the passageways being provided with openings, and needle valves threaded in said plug and extending across the supply pipe and co-operating with said openings to control pilot flow of gas through the passageways. 100

17. In an igniter device, a tubing, a torch head mounted at one end of said tubing, a plurality of torch jets carried by said torch head, a fuel supply, and an insert in the tubing dividing the same into a plurality of passages connecting said fuel supply with said torch jets. 110

18. In an igniter device, the combination with a plurality of burners and a main supply pipe therefor, of torch supply passageways extending along the main supply pipe, a valve member for each burner for controlling the flow of fuel from said main supply to its respective burner and to one of said torch supply passageways, a tubing, a torch head mounted on the outer end thereof, torch jets carried by said torch head, and a plurality of passageways in said tubing and connected one with each of said passageways, whereby actuation of said valve will supply gas to its burner and to its torch supply pas- 120 125 130

sageway to flash a jet of flames toward its respective burner.

19. An igniter device comprising the combination with a plurality of burners and a main supply pipe therefor, of a pair of torch supply pipes extending along the main supply pipe, a plurality of valves having their intake nipples secured in the main supply pipe between the torch-supply pipes and engaging said torch-supply pipes, connections between said valves and the burners, a main supply port in each valve communicating with the main supply pipe, a torch-supply port in each valve, each valve nipple having a transverse bore connecting said ports with a torch-supply pipe, a torch-head provided with a plurality of jets, and connections between the torch-supply pipes and corresponding jets of the torch-head.

20. In a device of the character described, 20 a main supply pipe, a pair of parallel auxiliary pipes mounted therein, one wall of the main pipe being bored in register with a bore extending through the auxiliary pipes, and a valve having a nipple threaded in 25 the main supply pipe bore and extending through the bore of the auxiliary pipes, said valve nipple closing the opening formed by said bore in the auxiliary pipes, and 30 passages in the valve nipple communicating with the interior of the main supply pipe and the auxiliary pipe.

In testimony that I claim the foregoing I have hereunto set my hand at Milwaukee, 35 in the county of Milwaukee and State of Wisconsin.

EMIL L. CLAUS.
